UNITED STATES PATENT OFFICE.

GEORGE B. GEISER, OF PHILADELPHIA, PENNSYLVANIA, ASSIGNOR TO BERGER BROTHERS COMPANY, OF PHILADELPHIA, PENNSYLVANIA, A CORPORATION OF PENNSYLVANIA.

GUTTER-HANGER CIRCLE.

Application filed July 1, 1925. Serial No. 40,720.

My invention relates to gutter hanger circles such as are used in connection with the supporting or hanging of gutters on buildings.

5 Heretofore various forms and types of gutter hangers circles have been produced, chief among which are those produced by casting and those produced from sheet metal.

The cast circles are perhaps the most 10 satisfactory form in use to-day, but are objectionable on account of their relatively high price. The circles produced from sheet metal have met with substantial success, but, though relatively cheap, are open to objection as not sufficiently strong and durable.

In accordance with my invention, I have produced a gutter hanger circle, which will be hereinafter described in detail, of a maximum strength and durability and at the 20 same time a circle which may be readily produced with a minimum of labor at a low cost on account of material.

Having indicated in a general way the nature and purpose of my invention, I will 25 proceed to a detailed description thereof with reference to the accompanying drawings, in which there is illustrated a preferred embodiment of my invention and in which—

Figure 1 is a plan view of a blank from 30 which the circle embodying my invention is formed.

Figure 2 is a cross sectional view of the blank shown in Figure 1.

Figure 3 is a side view of a circle embodying my invention.

Figure 4 is a rear view of the circle shown in Figure 3.

Figure 5 is an end view of a portion of the circle shown in Figure 3.

40 Figure 6 is a side view of the circle in gutter supporting relation to a roof indicated in section.

Figures 7, 8 and 9 are side views of modified form of circles embodying my invention.

45 The circle to be presently described in detail is formed from channel metal, as, for example, channel iron, copper, mild channel steel, or the like, by which will be understood metal of channel section.

50 The circle is essentially formed by bending the blank A, which is formed from a metal channel bar, preferably iron or copper.

In forming the blank, the web and one flange at one end of the blank are cut away square leaving the other flange which forms 55 an extension B. At the other end of the blank the web and the same flange are cut away on the bias, leaving an extension C.

The circle is formed by bending the blank into the form shown in Figure 3 to provide 60 a gutter supporting portion D, a gutter seat d' being formed by one of the flanges, and a hanger engaging portion E. The extensions B and C of the one flange are bent back to form a gutter engaging hook b and 65 a strap engaging hook c, respectively.

The hanger engaging portion E is provided with a series of spaced holes f and the web and one flange are pressed outwardly as shown at g, Figure 5, while the outer 70 flange is distorted as shown at h, Figure 4, to form a bead i, see Fig. 4, adapted to be entered and to lie within a perforated channelled portion of a hanger j adapted to be secured to the roof k of a building, as 75 shown in Figure 6. The bead i of the hanger engaging portion of the circle having been entered in the channel in the hanger, the circle is secured to the hanger by means of a bolt and nut l, the nut being 80 positioned between the flanges of the circle to prevent its turning. When the parts are so secured, the outer faces of the flanges of the circle and hanger are flush as shown in Fig. 6. 85

In the circle illustrated in Figure 3, it will be noted that the extensions B and C, which are bent to form the hooks b and c of the finished circle are extensions of the flange on the same side of the web which forms the gutter seat of the gutter supporting portion of the circle, while the flange on the other end of the web is displaced or distorted to form a portion of the hanger engaging bead. 95

The use of the circle will be clearly understood from an inspection of Figure 6, in which m indicates a gutter, one edge of which is engaged by hook b, while the other edge is secured by the usual strap n, one 100 end of which is engaged with the hook c.

The circles shown in Figures 7, 8 and 9 embody essentially the invention above described with slight variations in structural

detail and operate in essentially the same manner as does the circle illustrated in Figure 3 and operatively shown in Figure 6.

In Figure 7 is illustrated a circle in which 5 the hook *b* is formed partly by an extension of one of the flanges and partly by a portion of the flange sheared from the web.

In Figure 8 is illustrated a circle in which 10 the hook *c* is formed from an extension of the outer flange, while the hook *b* is formed from an extension of the inner flange.

In Figure 9 is illustrated a circle in which 15 the hanger engaging portion *D* is extended and the gutter engaging hook *b'* is formed by shearing a portion of the inner flange from the web.

As a result of my invention, it will be observed that a circle as well as the hanger may be formed from metal initially rolled 20 to channel section and possessive of great strength; and further formed with a minimum of bending strain on the metal.

Having now fully described my invention, what I claim and desire to protect by 25 Letters Patent is—

1. A gutter hanger circle formed from a

channel section, comprising a body portion for the support of a gutter and a hanger engaging portion formed by distortion of the web of the channel section, to form a seat 30 engaging portion for engaging a seat on a hanger.

2. A gutter hanger circle formed from a channel section, comprising a body portion for the support of a gutter and a hanger 35 engaging portion formed by distortion of the web and a portion of one of the flanges of the channel, to form an elongated seat engaging portion for engaging a seat on a 40 hanger.

3. A gutter hanger circle formed from a channel section, comprising a body portion for the support of a gutter and a hanger engaging portion formed by pressing the web outwardly to form a projection 45 adapted to be seated between the flanges of a channel section hanger.

In testimony of which invention, I have hereunto set my hand, at Philadelphia, Penna., on this 26th day of June, 1925.

GEORGE B. GEISER.
